DRYING AND FINISHING MACHINE

Application filed February 21, 1929, Serial No. 341,799, and in Great Britain March 5, 1928.

This invention relates to a combined drying and finishing machine for tubular textile fabrics.

One object of this invention is to provide a machine where the fabric is led over a tenter frame of flat formation to the finishing rolls or the like and drying air is supplied to the interior of the fabric whilst it is on the tenter frame. Another feature of this invention is that the tenter frame is arranged vertically so that when the air is supplied to the inside of the fabric the latter is dried uniformly on all sides. Another feature of this invention is that a continuous drying and finishing process is carried on for each length of the fabric. From the vertical disposition of the tenter frame the advantage is obtained that no part of the weight of the frame is carried on the fabric itself, which would give an uneven finish, whilst if it were proposed to fasten a frame to one end of a horizontal beam it would be necessary first to thread each length of fabric over the beam and then attach the frame.

In a preferred construction a machine according to this invention has a vertical tenter frame tapered at one end and made up of two lateral members each carrying a plurality of antifriction rollers and two or more, preferably adjustable, cross members joining the lateral members. This frame is used in conjunction with the known hollow cartridges on each of which one length of fabric from the hydro extractor is turned over, either by hand or by a known type of machine. Such cartridges are adapted to be removably mounted on the upturned end of the hot air supply pipe below the tenter frame. The lengths of fabric are drawn up over a flattened fish tail end piece placed over the upper end of the cartridge, pass over the tenter frame (which has its tapered end lowermost) to the finishing rolls and are baled up on suitable removable rolls above the finishing rolls. The tenter frame can be raised or lowered to allow the insertion of fresh cartridges, and the finishing rolls may be separable to allow this to take place. The elongated orifice of the fish tail

end piece delivers the drying air uniformly to the interior of the flattened hose on the tenter frame. This end piece is removable from the cartridge upon which the wet fabric is placed before being fed to the drying frame. 55

As the fabric passes over the antifriction rollers of the tenter frame hot air is blown with considerable force through the hollow cartridge and the hollow fish tail end piece into the inside of the fabric so that the latter is stretched and dried at the same time. The blower or fan and the heating unit may be of any known suitable type and form no part of this invention. It has 65 been found that the drying process is assisted by the provision of a stationary tube through which passes part of the tenter frame in its operative or fully lowered position. The effect of this tube is to induce 70 convection currents round the fabric. This tube may suitably be provided with glass panes through which the operator superintending the transfer of the fabric from the cartridge to the tenter frame can see whether 75 there is any tendency for the fabric to twist on the tenter frame. This is a fault which is especially undesirable with striped fabrics.

When the tenter frame is in its operative, 80 i. e. its fully lowered position, its central vertical shaft carrying the cross members is supported in a vertical sleeve rigidly mounted on the floor which projects axially into the turned up end of the air pipe. The 85 tenter frame can be lifted by a cable which when the finishing rolls are separated can be lowered and attached to the upper end of the central vertical shaft. The cable may carry stops to operate automatically a stopping device for the raising and lowering gear of the tenter frame. 90

With an unusually wide stretch of the tenter frame it sometimes happens that there is a tendency for the fabric to sag between 95 the antifriction rollers, which is especially undesirable with transversely striped fabrics. To counteract this, adjustable spring pressed "pulling up" wheels may be provided which can be brought into contact 100

with the outside of the fabric on the frame, the antifriction rollers of the frame projecting into the flanges of the "pulling up" wheels. Suitable driving means are provided for the "pulling up" wheels.

5 A machine constructed according to this invention is illustrated in the accompanying drawings. Figure 1 of the drawings shows a section through the end of the air pipe with the hollow cartridge mounted thereon. Figure 2 is a front view of the flattened fish tail end piece of the cartridge and of the lower tapered end of the tenter frame. Figure 3 shows the finishing rolls, their operating mechanism and the raising and lowering gear for the tenter frame. Figures 4, 5 and 6 show the automatic stop device associated with the tenter frame cable. Figure 7 is a view in the plane of Figure 3 of the tube for 10 inducing convection currents round the fabric. Figure 8 is a corresponding view to Figure 3 but in a plane at right angles thereto.

15 Figure 9 shows a side view partly broken away of an alternative form of the frame and Figure 10 shows a section on the line 20 IX-IX of Figure 9.

25 The removable cartridge 1 carrying a length of the fabric to be treated (not shown) is mounted on a flange 2 at the upturned end of the air pipe 3, the latter being carried by supports on the ground floor A of the factory. The cartridge 1 has the fish tail end piece 4 fitted over its upper end. 30 The tenter frame may either project below the level of the top of the fish tail when in its operative position, as shown in Figures 1 and 2, or may terminate above this level. For some cases the latter position is preferable.

35 The tenter frame, whose total length is preferably from 6 to 20 feet, consists of two lateral members comprising curved strips 5 carrying antifriction rollers 6, the latter being preferably of aluminium or aluminium alloy, and two cross members joining the lateral members and comprising rods 7 carried in hollow shafts 8. The rods 7 are attached to dummy rollers 6' mounted in the strips 5 similarly to the guide rollers 6. The length of the cross members can be adjusted by sliding the rods 7 in or out of the shafts 8, removable pins 9 co-operating with holes 10 in rods 7 to hold the rods in their adjusted position. The shafts 8 are centrally carried in holes bored in solid sections of a central vertical shaft 11 and are brazed thereto. The shaft 11 which is hollow over most of its length can be attached at its upper end to a cable 12 by means of which the tenter frame can be raised and lowered. When the tenter frame is lowered into its operative position the lower end of the shaft 11 passes into and is supported by a hollow sleeve 13 which is

rigidly mounted on the floor A and projects axially through the up-turned end of the air pipe. The sleeve 13 is bell-mouthed to facilitate location of the shaft 11. The tenter frame is entirely supported by rod 11 which is maintained vertical in the socket 13 and is prevented from swinging by the outside rollers 16 which are operated by the right and left screw on shaft 17 to approach and recede from rod 11 equally. By 10 terminating socket 13 below the base of cartridge 1, it is apparent that when the rod 11 is raised there is nothing to obstruct the replacement of the flanged cartridge 1.

15 When the tenter frame is in its operative position, part of it passes through the frame 14 which is fastened to the under side of the upper floor B of the factory, as shown in Figure 7. The object of this tube is to act as a funnel by inducing convection currents 20 of air around the fabric, most of the heated air passing through the fabric is thus confined to pass over the outer surface of the fabric. To enable the operator on the floor below, who is superintending the transfer of the fabric from the cartridge to the tenter frame, to inspect the fabric on the frame, the stationary vertical tube 14 is provided with glass panes 15. Alternatively the tube 25 or frame 14 could be made of transparent material.

30 It sometimes happens, especially when a big stretch is required on the tenter frame, that the fabric sags. To counteract this, grooved "pulling up" wheels 16 (Figure 8) 100 are provided, one at each side of the tenter frame, which may be brought into contact with the outside of the fabric by turning the left and right hand threaded shaft 17 by means of the hand wheel 18. When the wheels 16 are in contact with the fabric the antifriction rollers 6 project into the groove of the wheels 16. The wheels 16 are preferably covered with a material such as rubber or felt in order to obtain a good grip on the fabric. Springs 19 act on the wheels 16 to impart an even pressure. The wheels 16 are driven from the main pulley shaft 20 through the variable cone gear 21, the chain gear 22 and the bevel gear 23. More than one pair of wheels 16 may be provided. Rubber coated wheels in contact with the outside of a tubular fabric on a stretcher for assisting the passage of the fabric over the stretcher are not in themselves new.

35 The tenter frame can be raised when the finishing rolls are separated by attaching cable 12 to the upper end of shaft 11 and winding up the other end of cable 12 on the drum 24. The drum 24 is driven by the main shaft 20 through a reversing clutch 25 controlled by the handle 26. When the tenter frame has reached the upper or lower limit of its travel a stop on the cable operates a plunger 27 (Figures 4 and 6). The 120

plunger 27 is mounted on the top beam of the upper framework C and co-operates with a pivoted lever 28 mounted on the same beam to which is attached the end of a rod 29. The rod 29 operates a rod 30 through a double armed lever 31 (Figure 5) pivoted on the same beam as plunger 27 and lever 28 whilst the other end of the rod 30 is attached to a catch 32 adapted to act on the clutch 25 to disconnect the drum 24 from the driving shaft 20.

The finishing roll 33 is mounted so as to rotate on the stationary shaft 34 and is driven from the main shaft 20 through a variable speed gear D and a worm gear 35. The other finishing roll 36 is mounted so as to rotate on the shaft 37 supported in bearings carried on the shafts 38, 38'. The rolls 33 and 36 can be separated or closed by moving the roll 36 by means of the threaded shaft 39 operated by a handwheel 40 through a two speed gear 41. The rolls are brought into contact on top gear, the lower gear is engaged by means of the hand wheel 40 through the handle 42 and pressure is brought to bear on roll 36 through springs 43. The amount of such pressure is indicated on a scale 44. When rolls 33 and 36 are in contact gear wheels 45 and 46 fast to them respectively mesh with each other so that roll 33 drives roll 36.

The fabric passing out of the finishing rolls 33, 36 is baled up on a removable roll 47 inserted in slots 48 made in the machine frame.

Where for any purpose it is desired to raise the tenter frame by hand, the fast pulley 49 is freed from the shaft by means of a latch 50 (the belt being shifted to the loose pulley 51 whilst the latch is being operated) and a handle 52 is moved to put the drum 24 into gear with a hand wheel 53 through a dog clutch 54.

The operation of the machine is, therefore, as follows:—

A length of fabric from the hydro extractor is turned over on to the hollow cartridge 1. The tenter frame being raised, the cartridge is fitted over the air pipe flange 2 and the fish tail 4 is fitted over the upper end of the cartridge. The tenter frame is adjusted to the correct width by removing the pins 9 from the holes 10, sliding the rods 7 into or out of the shafts 8 and replacing the pins. (For some purposes it may be desirable to have the two cross members of the frame different lengths). The handle 26 is moved to start the drum 24 paying out the cable 12 to lower the tenter frame. The lower end of shaft 11 enters sleeve 13. When the frame reaches its lowest position, a stop on cable 12 operates plunger 27 to stop the drum 24 through rod 30. Cable 12 is then detached from shaft 11 and is raised again by moving handle 26

in the reverse direction, drum 24 being again automatically stopped when the cable reaches its uppermost position. The fabric is now passed over the fish tail on to the tenter frame either from the ground floor or by means of hooked tapes passed down from the floor above, and is raised to the level of the rolls 33, 36. These rolls are now closed and adjusted to the correct pressure by means of the hand wheel 40, and pulling up wheels 76

16 are closed on the outside of the fabric. The fabric passes through the rolls 33, 36, hot air being supplied to the interior of the tenter frame through the pipe 3, and is baled up on roll 47. When a complete 76 length of fabric has been finished, the roll 47 is removed from slots 48, rolls 33, 36 are separated, cable 12 lowered and attached to shaft 11, and the tenter frame is raised to allow a fresh cartridge to be inserted. 76

As shown on Figs. 9 and 10 various modifications may be made in the machine within the scope of the appended claims. Instead of providing the sleeve 13 for positioning the shaft 11, this shaft can be carried in sleeve members 55 centrally mounted in brackets inside the fish tail end piece 4. Such an arrangement would be of value for reducing the total height of the machine because then the distance which the tenter frame must be moved to insert a fresh cartridge is much reduced. 85

In another modification loose rollers 56 are mounted in brackets 57 on the outside of the flattened sides of the fish tail 4, the axes of these rollers being parallel to the plane of the flattened sides, and rods 58 coaxial with these rollers 56 are mounted above the rollers, the distance apart of the axes of the rods being less than that of the axes of the rollers. The fabric shown in dot and dash lines in Fig. 10 passes over the rollers 56 and under the rods 58 on its upward path to the tenter frame. By adjusting the height of the rods 58, tension can be applied to the centre of the fabric, and this roller and rod mechanism can be considered as a "pulling down" mechanism. 105

In another modification the two speed gear 41 is omitted. 110

What I claim is:

1. A combined drying and finishing machine for tubular textile fabrics comprising a central shaft, a vertically disposed flat tenter frame mounted on said shaft and formed of a pair of parallel depending members, a hot air supply pipe with its outlet directed vertically upwards in the direction of the centre line of said vertically disposed tenter frame, a removable hollow cartridge adapted to carry a length of the fabric to be treated mounted on said air supply pipe and below said tenter frame, a hollow fish tail end piece with an elongated orifice mounted on the upper end of said cartridge, 125

raising and lowering means for said frame and separable finishing rolls above said frame when in its operative position.

5 2. A combined drying and finishing machine for tubular textile fabrics comprising a central shaft, a vertically disposed flat tenter frame mounted on said shaft and formed of a pair of parallel depending members, a stationary vertical tube of greater 10 internal dimensions than the external dimensions of said frame, said tube being open at both ends to induce convection air currents therein and surrounding said frame, fabric finishing means disposed beyond and near the upper end of said frame and a hot air 15 supply conduit directed into the interior of said frame.

20 3. A combined drying and finishing machine for tubular textile fabrics comprising a vertically disposed and movable flat tenter frame, a cable with one end detachably connected to said frame, a winding up drum for said cable, a clutch device interposed between said drum and its driving 25 means, disengaging mechanism for said clutch device, stops on said cable co-operating with said disengaging mechanism, separable finishing rolls above said frame when in its operative position and a hot air supply 30 conduit directed into the interior of the tenter frame.

35 4. A combined drying and finishing machine for tubular textile fabrics comprising a central shaft, a vertically disposed flat tenter frame mounted on said shaft and formed of a pair of parallel depending members, power actuated raising and lowering gear for said frame, manually actuated raising and lowering gear for said frame, 40 means for disconnecting said power actuated gear and a clutch for connecting said manually actuated gear, separable finishing rolls above said frame when in its operative position and a hot air supply conduit directed 45 into the interior of said frame.

50 5. A combined drying and finishing machine for tubular textile fabrics comprising a vertically disposed tenter frame comprising two depending members bent inwards at their lower ends and each carrying anti-friction means for the fabric and members joining said lateral members, a hot air supply pipe with its outlet directed upwards towards the centre of said frame and arranged below said frame, a removable hollow cartridge for carrying a length of the fabric to be treated mounted above the outlet of said air pipe, a hollow fish tail end piece mounted on the upper end of said cartridge 55 immediately below said frame, raising and lowering means for said frame, spring pressed positively driven wheels adjustable transversely to the direction of movement of the fabric disposed outside 60 said frame and, when so adjusted, in contact 65

with the fabric on said frame and separable finishing rolls above said frame when in its operative position.

6. A drying machine for tubular fabrics comprising a removable hollow receiving cartridge upon the outside of which the wet fabric is placed, a frame above said cartridge arranged to receive the fabric from said cartridge for drying purposes, a vertical shaft for supporting said frame and a fixed sleeve in the axial line of and below the base of said cartridge for receiving and supporting said shaft.

7. A combined drying and finishing machine for tubular textile fabrics comprising a removable vertical cartridge upon the outside of which the wet fabric is placed, a fixed sleeve located on the axial line of said cartridge and below the base of said cartridge, a vertical shaft supported by said sleeve, a drying frame comprising a pair of parallel members for receiving the fabric from said cartridge, said frame being mounted on said vertical shaft, an air supply directed into the interior of the fabric on said frame through said cartridge and finishing means disposed at the end of said frame for taking up the fabric from said frame.

8. A combined drying and finishing machine for tubular fabrics comprising a removable vertical cartridge upon the outside of which the wet fabric is placed, a central shaft, means located on the axial line of said cartridge and substantially below the base of said cartridge for vertically supporting said shaft, a flat tenter frame mounted on said shaft and arranged to receive the fabric from said cartridge, an air supply directed into the interior of said fabric on said frame through said cartridge and means for taking up the fabric from said frame.

9. A drying machine for fabrics comprising a receiving cartridge, a vertically disposed and movable tenter frame relative to said cartridge upon which the fabric is stretched for drying purposes, finishing rolls for receiving the dried fabric from said frame, means for operating said machine including means for raising and lowering said tenter frame and means for automatically stopping the movement of said tenter frame in a predetermined position.

10. A drying machine for fabrics comprising a tenter frame having a pair of depending members vertically movable for receiving the fabric to be dried, means for feeding the fabric to the lower end of said tenter frame, finishing rolls for receiving the fabric from the upper end of said tenter frame, means for operating said machine including a cable for raising and lowering said tenter frame and means for automatically stopping the movement of said tenter

frame in a predetermined position when the machine is in operation.

11. A drying machine for tubular fabrics comprising a receiving cartridge for receiving the wet fabric, a flat tenter frame comprising a pair of depending, spaced, members vertically disposed relative to said cartridge upon which the fabric is spread for drying purposes, an elongated orifice for 5 said cartridge with its longer axis aligning with said frame and a stream of air directed into the interior of said fabric on said tenter frame through said cartridge and orifice.

10 In testimony whereof I have signed my 15 name to this specification.

EMILE BERNARD BATES.
